UNITED STATES PATENT OFFICE.

ALLEN F. CARVER, OF NEW YORK, N. Y.

ELECTRIC-DRIVEN TOOL.

No. 886,678.

Specification of Letters Patent.

Patented May 5, 1908.

Application filed February 5, 1907. Serial No. 355,888.

To all whom it may concern:

Be it known that I, ALLEN F. CARVER, a citizen of the United States, residing at New York, in the county of New York and State of New York, have invented new and useful Improvements in Electric-Driven Tools, of which the following is a specification.

My invention relates to electric reciprocating tools and devices of all kinds, such as riveting, chipping and calking hammers, rock drills, etc., and has for its object the repelling of the operating parts of the hammer and the relief of these parts of magnetic attraction which would otherwise impair their working, also means for more effectually preventing sparking in certain contact points all of which will be hereinafter more fully explained in this specification, set forth in the claims and illustrated in the drawings.

Figure 1 is a diagrammatic view of a hammer with its operating adjuncts and its electric circuits. Fig. 2 is a sectional view of the tool holding chuck and the shank of the drill. Fig. 3 is a face view of the chuck.

A serious objection in electric hammers has been the magnetizing of the hard-metal parts which are necessary in their construction and the consequent attraction of these parts to each other so that their rapid action is seriously impaired and the utility of the tool reduced to a minimum and it is for the purpose of overcoming these objections that the present invention is desired and also to prevent sparking of certain parts when the circuit is broken and as these breaks are very frequent and numerous it leads to serious wearing away of said contacts.

In the drawing the hammer 5 is provided with the usual tool 6 and plunger 7, the latter having behind it a spring or other cushion 8 to prevent too sudden a return of the plunger to the rear of the hammer and a battering action at that end of the tool. This spring is inclosed in a casing 9 or otherwise arranged as may be found desirable.

The hammer is wound with a plurality of coils; but preferably two coils 10 and 11, the latter being smaller than the former on account of less work being required from it and as shown in the drawings these coils are wound in the same direction but the electric connections are so made as to produce like magnetic polarity at their adjacent ends; the common return wire 21 is connected to the inside of coil 10 and to the outside end of coil 11. By this simple and efficient means the

plunger and shank are so magnetized with like polarity that any attraction or sticking of these parts is avoided during the return stroke.

The operation of the hammer is controlled by a plunger 12 having a button 13 to operate same and a spring 14 to return it to its normal position. This plunger controls four springs 15, 16, 17 and 18 which are adapted to control certain currents which influence the hammer to accomplish the results sought to be obtained. The source of electricity is illustrated by the points 19 and 20, the point 19 supplying the hammer with the current by means of the wire 21 which is connected with the interior turn of coil 10 and the exterior turn of coil 11, this circuit being open until the button 13 is depressed as will be herein-after explained. A connection 22 leads from this line to the spring 15 and when it is desired to start the hammer, by pressing the plunger and bringing the contact 15 and 16 together a circuit is set up in the direction indicated by the arrows → and which includes a coil 24 surrounded by a separate coil 23. These coils contain and energize a core 25 which attracts an armature 26 and closes the contacts 27 establishing a circuit indicated by the arrows → which passes through the coil 23 and holds the armature 26 more firmly against the core 25 and also passes through the shaft 41 of the commutator 28 the segment 45 and brush 46. When the plunger 12 is further depressed the contacts on the spring 15, 16 and 17 are closed and a circuit is created which includes in it an electro-magnet 29 controlling a lever 30 which carries brushes 31 and 32 controlling the coils 10 and 11 respectively. The tendency of the solenoid 29 is to attract a core 33 which turns the lever 30 on its pivotal point and throws the brushes 31 and 32 a greater distance away from the brushes 34 and 35 with which they are respectively connected in multiple thus increasing the period of energization of the coils during each revolution of the commutator. It may be desirable to regulate this distance or period for the flow of current through the coils and in order to accomplish this I provide the stem 36 of the core 33 with a tooth 37 which is adapted to come in contact with a pawl 38 carried by an armature 39 which is actuated by an electro-magnet 40. Instead of one tooth 37 several of these may be arranged on the stem with an armature, pawl and operating magnet and con-

tact spring for the magnet added to the switch controlled by the operator of the tool so that a step-by-step action may be arranged to permit the increase of the period of flow of the current. This electro-magnet 40 is controlled by the contact on the spring 18 which when the plunger 12 is depressed far enough closes a circuit including this electro-magnet and elevates the pawl 38 so that the solenoid 33 may travel its full extent. This device permits of the variation of the flow of current through the coils without the use of dead resistances and affords a very simple means of accomplishing this object. When the button 13 is released the reverse order takes place, except in case the segment 45 is in contact with the brush 46. While this condition exists the armature 26 will be held by the core 25 and the current continues to flow in the main line to the commutator. When the commutator revolves so as to bring the opening in ring 45 to the point of contact between this ring 45 and brush 46, the coil 23 will be deenergized as there is now no magnetism induced in core 25 by either coil 24 or coil 23 the armature 25 will be released breaking the main line to the commutator at 27. No sparking can occur at the contact points 27 when above action takes place as the break in the ring 45 is so placed relative to the segment 28' that coil 23 can never be deenergized as long as the segment 28' is feeding current to brushes 34, 31, 42, 43, 35 and 32. As illustrated in the drawing the segment 28' is shown just about to leave the brushes 31 and 34, the commutator moving in the direction shown by the arrow →, but when it finally does leave these brushes the current still flows through the coil 10 by the brushes 42 and 43 and the resistance coil 44. As the wheel 28 revolves still further the segment 28' comes into contact with brushes 35 and 32 allowing the current to flow through coil 11, as these brushes control the current passing through this coil and as the segment is still making contact with the brush 43 there is still a greatly reduced current flowing through coil 10 in consequence of the resistance coil 44 being in that circuit. When the above action is taking place the end of the tool 6 will be of the same polarity as the end of the plunger 7 which is then in contact with it and the plunger and tool will not be attracted towards each other but repelled, and the more strongly energized coil 11 is able to retract the plunger 7 from the shank of the tool so as to be ready for another blow when the coil 11 is deenergized and coil 10 is energized to its full strength again.

While I have not shown modifications for the various means above described for accomplishing these results it is obvious that various means may be employed without departing from the essential features above described and shown. For instance that by

increasing or diminishing the relative position within the coil 44 the coil 10 and 11 at which the plunger and tool shank will release perfectly can be varied.

In an electric tool driver proportioned as shown, the tool shank is partly within the field of coil 10 and the plunger 7 is also partly within the field of coil 10, when the coil 10 is energized full strength and end of plunger 7 is in such a position that it is separated from the end of the tool shank, there are set up lines of magnetic force tending to make the ends of the plunger and the tool shank of opposite polarity, and the plunger will be attracted with great force towards the tool shank. As the commutator revolves a resistance 44 is cut in in series with this coil 10 reducing the current and magnetic intensity of the lines of force. The end of the plunger 7 and the tool shank are still of opposite polarity and stick together. If now, however, coil 11 is suddenly energized full strength at the same time that coil 10 is weakly energized, the magnetic lines of force induced by coil 11 which are of opposite polarity to those induced by coil 10, will flow through plunger 7 until they meet the lines of force flowing in the opposite direction in tool shank, due to action of coil 10. This action is possible because as coil 10 is now relatively weak to coil 11, coil 11 is able to reverse the polarity of that part of plunger 7 lying within coil 10. Coil 10, however, is kept strong enough to retain the original polarity of tool shank, and hence the releasing of plunger from tool shank. When this occurs the magnetic polarity of the end of tool shank, and end of the plunger 7 will be alike and will repel each other and the coil 11 will retract the plunger 7 which is then in a position to be acted upon for another forward movement towards tool shank when the coil 11 is deenergized and coil 10 is energized full strength again.

What I claim as new and desire to secure by Letters Patent is:

1. In an electric tool driver, the combination with a plunger, of coils adapted to impart a different polarity to the plunger when it has about completed its stroke, and means connected with the tool for reducing the current in one coil while a greater current flows through the other coil.

2. In an electric tool driver, the combination with a plunger, of two coils adapted to change the polarity of the plunger at the end of its stroke, and means connected with the tool for alternating the magnetic strength from one coil to the other for every stroke of said plunger.

3. In an electric tool driver, the combination with a plunger, of coils of opposite magnetic polarity, and means for changing the relative strengths of the magnetic polarities for every stroke of said plunger.

4. In an electric tool driver, means under the control of the operator for electrically varying the relative period of energization and deenergization of the coils.
5. In an electric tool driver, the combination with a plunger, of a tool operated by the plunger, coils enveloping the plunger and actuating same, electric circuits including the coils, means for alternating the current strength through the circuits, and means for varying the period of passage of the current through the circuits.
6. In an electric tool driver, the combination with a plunger, of a tool operated by the plunger, coils enveloping the plunger and actuating same, electric circuits including the coils, means for alternating the current strength through the circuits, and means for electrically varying the period of passage of the current through the circuits.
7. In an electric tool driver, the combination of the tool, of a plunger operating upon same, coils surrounding the plunger and actuating it, electric circuits, means for varying the period of flow of the current through the circuits and means for varying the polarity of the plunger and the tool so as to cause them to repel each other.
8. In an electric tool driver, the combination with the tool, of a plunger operating upon same, coils surrounding the plunger and one end of the tool and adapted to produce repelling polarity in the tool and plunger when the coils are energized together, a commutator with brushes adapted to close the circuits leading to the coils, an electro-magnet provided with means for altering the relationship between the brushes, an electro-magnet adapted to operate a switch to close the circuit operating the tool, a second electro-magnet wound around the latter electro-magnet and adapted to hold the switch in its closed position and a switch under the control of the operator and adapted to close the circuits controlling these electro-magnets and on further movement to close the circuit of the electro-magnet controlling the brushes.
9. In an electric tool driver, the combination with constantly energized coils adapted to produce opposite polarity, of electrical means for varying the length of time that the current flows through the coils, adjusting means for the above controlling means and a circuit closing electro-magnet working in conjunction with a separate coil on same, a magnet for keeping the switch closed and a plunger with a plurality of contact carrying springs which are operated upon by the plunger to close and operate the circuits control-
- ling the means for the flow of electricity, the adjusting means and the closing circuit magnet.
10. In an electric tool driver, the combination with a plunger of a tool operated thereby, constantly energized coils adapted to produce different polarity surrounding the plunger, an electric circuit embracing the coils, an electro-magnet in the circuit, a switch controlled by the operator adapted to close the circuit and energize the electro-magnet, a second electric circuit including an armature actuated by the electro-magnet, an interrupter in the circuit, a second electro-magnet in the circuit and resistance coils adapted to be thrown in to the coils when a releasing action is desired between the plunger and tool.
11. In an electric tool driver, the combination with a plunger, of a tool operated thereby, constantly energized coils surrounding the plunger and adapted to reciprocate the same and to produce different polarity and means controlled by the operator of the tool for varying the intensity of the current to increase or diminish the force of the blow.
12. In combination with an electric tool driver, an electro-magnet switch consisting of a stationary core, a coil wound on same, an armature adapted to be acted on by said core and coil, and a switch in the main circuit operated by the movement of said armature, said electro-magnet switch controlled by another switch under the control of the operator of the tool.
13. In combination with an electric tool driver, an electro-magnetic switch wound with a double winding of same polarity controlling the main line, and adapted to open the main line without serious sparking at the switch contacts, substantially as described.
14. In combination with an electric tool driver an electro-magnetic switch controlling the main line wound with two coils of same polarity one under the control of operator of tool driver, and the other controlled by such means that it will hold said magnetic switch closed independent of action of coil under control of operator, and only allowing main switch to operate such times as main line has little or no current flowing in it, thus preventing sparking at contacts of said electro-magnetic switch.

In testimony whereof, I affix my signature in presence of two witnesses.
